UNITED STATES PATENT OFFICE.

EDWIN M. SILVERMANN, OF NEW YORK, N. Y., ASSIGNOR TO HARRIS SUSPENDER COMPANY, A COPARTNERSHIP, COMPOSED OF EDWIN M. SILVERMANN AND HARRY W. SILVERMANN, OF NEW YORK, N. Y.

GARMENT-SUPPORTER.

1,322,836.

Specification of Letters Patent.

Patented Nov. 25, 1919.

Application filed March 16, 1918. Serial No. 222,798.

To all whom it may concern:

Be it known that I, EDWIN M. SILVERMANN, a citizen of the United States, residing at New York city, in the county of New York and State of New York, have invented certain new and useful Improvements in Garment-Supporters, of which the following is a specification.

My invention relates to improvements in garment supporters for children and it is my object to produce a supporter which will aid in correcting round shoulders and stooping, which will evenly distribute the weight of the garments, which will securely hold up the garments and which can be easily adjusted to different sizes.

The drawing is a perspective view of my improved supporter.

The supporter consists of a waist band 1 adapted to encircle the waist of the wearer. This may be secured together at the front by a button 2 and button hole 3.

An end piece 4 is secured to the middle of the back of the waist band and has the metal loop 5 at its upper end which slidably engages a back strap 6 which may be adjusted for length by means of the slide buckle 7.

Shoulder straps 8 and 9 extend from the upper end of the back strap and pass through slide buckles 10 and 11 with their free ends detachably secured to the waist band 1 by fasteners 12 and 13. A plurality of fasteners are provided to permit the supporter to be fitted to children of different sizes.

Each buckle 10 and 11 has a suspender end 14 and 15 extending down to the waist band 1 to which it is secured.

Under arm straps 16 and 17 extend from the upper end of the back strap 6 and from the rear ends of the shoulder straps 8 and 9

to a point adjacent to the front or free ends of the shoulder straps.

The back strap 6 and the shoulder straps 8 and 9 are preferably made of elastic webbing while the remaining straps are preferably non-elastic.

Buttons 18 are secured to the waist band 1 at suitable intervals to which the garments may be buttoned.

In use the shoulder straps go over the shoulders, the under arms straps under the arms and the waist band around the waist so that the supporter will not slip from the shoulders and the under arms straps will bear their share of the weight of the garments which prevents the child from stooping and becoming round shouldered. Being garterless it is particularly adapted for summer wear with socks.

I claim:

A garment supporter comprising a waist band, an adjustable back strap secured to the middle portion of the rear of the waist band, a pair of shoulder straps extending from the upper end of the back strap to the forward portion of the waist band, suspender ends slidably secured to the front of the shoulder straps with their lower ends secured to the waist band, a pair of under arm straps also extending from the upper end of the back strap to the shoulder straps at a point adjacent to the waist band, a plurality of fastening devices on the shoulder straps and waist band whereby their relative positions may be changed, and means on the waist band adapted to engage portions of the garments to be supported.

In testimony whereof I have affixed my signature.

EDWIN M. SILVERMANN.
